UNITED STATES PATENT OFFICE

2,501,395

CURTAIN STRETCHING FRAME

John A. Leas, Springfield, Ill.

Application April 5, 1947, Serial No. 739,667

6 Claims. (Cl. 45—24)

1

This invention relates to an improvement in stretching and drying frames such as are much used for stretching and drying curtains.

An object of the invention is to provide a frame which does not present exposed sharp points such as pins or nails, that are likely to scratch the hands of the user either while applying the material to be stretched and dried or while assembling the frame.

Another object is to provide reenforcement means for the piercing members of the device which pierce the material to be stretched and dried so as to prevent said members from being bent by the tension exerted upon them by said material. This reenforcement means permits the use of piercing members of small diameter thus reducing the danger of damage to the threads of the material being acted upon and preventing the formation of large and unsightly holes in said material.

Another object is to so position the piercing members in the frame members of the device that none of the frame members may disturb or damage any of the piercing members while the frame members are being assembled.

Other objects and advantages will appear in course of the following specification, and with all of said objects and advantages in view this invention consists in the several novel features hereinafter fully set forth and more particularly defined in the appended claims.

The invention is clearly illustrated in the accompanying drawing in which:

Fig. 1 is a perspective view of a complete and assembled stretching and drying frame, embodying a simple form of the invention;

Fig. 2 is an enlarged cross section taken along the line 2—2 of Fig. 1;

Fig. 3 is a fragmental front elevation of the horizontal frame member seen in Fig. 2;

Fig. 4 is a perspective view of one of the piercing members; and

Fig. 5 is a fragmental front elevation of a slightly modified form of frame member.

Referring to said drawing in which like numbers refer to like members in the various views, and referring first to Figs. 1 through 4, inclusive, it will be seen that the frame consists of two main horizontal frame members 1 (see Fig. 1), each composed of two sections 1a hinged together at the centers by hinges 7, whereby they may be folded up for ease in storing. The frame members carry piercing members 8 on one side at relatively closely spaced intervals. The two main frame members 1 are supported by two other substantially upright frame members 2 which also carry piercing members 8 on one side. The frame members 2 also carry legs 3 hinged thereto by hinges 5 so that they may be folded for storage and constrained by flexible members 4 which connect the legs 3 to the frame members 2 so that

2

they will support the entire structure in the manner of an easel. The member 6 is a spreader which is placed near the center of the frame to resist sagging of frame members 1 and also to assist in supporting the entire structure. All of the frame members 1, 2 and 6 are provided with transverse holes 17 through which bolts 17a may be inserted with thumb nuts on their ends to fasten the members into rigid frame and at the same time to provide adjustment for varying sizes of material to be stretched and dried.

Each of the frame members 1 and 2 is formed on one face 19 with transversely extending relatively closely spaced slots 19a having sloping bottoms, and each frame member is provided with a groove 13, in one face to receive the coiled ends 11, of the piercing members 8. A rod 18 is passed through the coiled ends 11 of the piercing members 8, and said rod is secured in the groove 13 at intervals with double pointed tacks or staples 18a. Each coil 11 has a projecting end 12 which, bears against the bottom of a slot 19a producing a torsional stress in the coil 11 tending to rotate the piercing member 8 about the rod 18. Since the coil 11 is of such internal diameter as to be free to rotate on rod 18 the net result of said torsional stress is to cause the thumb piece or loop 9 of the piercing member 8 to bear tightly on the surface 15 of the frame member. Each piercing member may comprise a length of resilient wire, coiled at one end to provide the coil 11, and bent up at its other end to form a thumb piece or loop 9, and a downwardly projecting piercing pin 10.

The surface 15 of each frame member is at a level sufficiently spaced from the general level of the surface 19 of the frame member that when the frame members are assembled into a frame and secured tightly together with the bolts the piercing members 8 will not be damaged by the frame members which intersect them. The normal position of the piercing members 8 is, therefore, adjacent the bottoms of the transverse slots 19a, with the thumb-loops 9 tightly pressed against surface 15 and the piercing pins 10 disposed in a longitudinal slot 16 in the frame member.

It will be noted that the thumb-loop 9 of the piercing member 8 does not project beyond surface 20 of the frame member, therefore, if in handling the frame one of the frame members is dropped or struck against any object, the surface 20 thereof offers considerable protection against bending of the piercing members 8. The surface 14 is inclined as shown in Fig. 2 to provide purchase for the user's thumb or fingers against loop 9 in order that the piercing members 8 may be manipulated in the normal operation of the device.

In the normal operation the piercing members 8 are raised one at a time to some position such as is shown in dotted lines in Fig. 2, by upward

pressure exerted against loop 9 by the user's fingers. The edge of the material to be stretched is then inserted under the piercing member and against surface 19 of frame member and covering slot 16 and the pressure on loop 9 is then released permitting the piercing member to snap back by the spring action to its original position, causing the piercing pin 10 to pierce the material to be stretched and reenter the slot 16 where it is then reenforced and assisted against the pull of the material by the edge of slot 16. This reenforcement by the edge of the slot 16 prevents bending of the piercing pin 10 by the pull of the material being stretched.

In the modified form of the invention illustrated in Fig. 5, individual recesses or sockets 16a for receiving the piercing pins are substituted for the groove 16 of the preferred form of the invention. The edge of the recess or socket functions as a reinforcement for the piercing pin.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. In a stretching and drying frame, longitudinal and transverse frame members, means for securing said members together to form a frame, each frame member being formed in one face with spaced slots extending transversely of the frame member, and with a groove opening to said slots adjacent one edge of the frame member, piercing members, one contained in each slot and being formed with a coiled end terminating in a projecting end portion, and a rod extending through said groove and through said coiled ends, each piercing member being formed at its other end with a thumb piece and a piercing pin, said coiled end of each piercing member functioning to hold the thumb piece against the slotted face of the frame member with the piercing pin held in a depression in said slotted face of the frame member.

2. In a stretching and drying frame, longitudinal and transverse frame members, means to secure said frame members together to form a frame, each frame member being formed in one face with transversely extending slots, said face being offset inwardly adjacent one edge of the frame member, piercing members, one in each slot and formed at one end with a coil terminating in a projecting end adapted to engage the bottom of the slot and urge the other end of the piercing member against said offset part of the slotted face, and a rod secured to said frame member and extending through the coiled ends of the piercing members, the free end of each piercing member being formed with a thumb loop and a piercing pin, the piercing pin being arranged to extend into a recess formed in the slotted face of the frame member.

3. In a stretching and drying frame, horizontal and transverse frame members, removably secured together to form a frame, all of the frame members having on corresponding faces thereof, transversely extending slots formed with inclined bottoms and terminating at their lower ends in a longitudinally extending groove, inclined piercing members, one in each slot with the lower end in the form of a spring coil terminating in a

projecting end, and a rod extending through said groove and through said spring coils and secured to the frame member, the upper end of each piercing member being formed with a thumb loop spring pressed against the slotted face of the frame member, and also formed with a piercing pin arranged to normally extend into a recess formed in the slotted face of the frame member.

4. In a stretching and drying frame, longitudinal and transverse frame members, means for securing said members together to form a frame, each frame member being formed in one face with spaced transverse slots, the bottoms of which are inclined, and also formed with a groove opening to said slots at the lower ends of the bottoms of said slots, piercing members, one contained in each slot and being formed with a coiled end terminating in a projecting end portion, and a rod extending through said groove and through said coiled ends, each piercing member being formed at its other end with a thumb loop and a piercing pin, said coiled end of each piercing member functioning to hold the thumb loop against the slotted face of the frame member with the piercing pin held in a depression in said slotted face of the frame member.

5. In a stretching and drying frame, longitudinal and transverse frame members, means to secure said frame members together to form a frame, each frame member being formed in one face with transversely extending slots, said face being offset inwardly adjacent one edge of the frame member, and terminating in an inclined edge portion, piercing members one in each slot and formed at one end with a coil terminating in a projecting end adapted to engage the bottom of the slot and urge the other end of the piercing member against said offset part of the slotted face, and a rod secured to said frame member and extending through the coiled ends of the piercing members, the free end of each piercing member being formed with a thumb loop and a piercing pin, the piercing pin being arranged to extend into a recess formed in the slotted face of the frame member.

6. In a stretching and drying frame, horizontal and transverse frame members, removably secured together to form a frame, all of the frame members having on corresponding faces thereof, transversely extending slots formed with inclined bottoms and terminating at their lower ends in a longitudinally extending groove, inclined piercing members, one in each slot with the lower end in the form of a spring terminating in a projecting end, a rod extending through said groove and through said spring coils and secured to a frame member, the upper end of each piercing member being formed with a thumb loop spring pressed against the slotted face of the frame member, and also formed with a piercing pin arranged to normally extend into a groove formed in the slotted face of the frame member.
